US00D823332S

(12) **United States Design Patent** (10) Patent No.: US D823,332 S
Rowe et al. (45) Date of Patent: ** Jul. 17, 2018

- (54) **DISPLAY SCREEN OR A PORTION THEREOF WITH GRAPHICAL USER INTERFACE** H04N 21/00; H04N 21/234; H04N 21/431; H04N 21/4312; H04N 21/4314; H04N 21/4316

(71) Applicant: **Cox Automotive, Inc.**, Atlanta, GA (US)

(72) Inventors: **Shannon Rowe**, Atlanta, GA (US); **Lamar Flowers**, Atlanta, GA (US); **Drew Buchter**, Atlanta, GA (US); **Chuck Konfrst**, Atlanta, GA (US)

(73) Assignee: **COX AUTOMOTIVE, INC.**, Atlanta, GA (US)

(**) Term: **15 Years**

(21) Appl. No.: **29/595,698**

(22) Filed: **Mar. 1, 2017**

(51) LOC (11) Cl. **14-04**

(52) U.S. Cl. **USPC D14/486**

(57) **CLAIM**

The ornamental design for a display screen or a portion thereof with graphical user interface, as shown and described.

DESCRIPTION

The FIGURE is a view of a display screen or a portion thereof with graphical user interface. The outermost broken line illustrates a display screen or a portion thereof and forms no part of the claimed design. The remaining broken lines illustrate portions of the graphical user interface that form no part of the claimed design.

1 Claim, 1 Drawing Sheet
